UNITED STATES PATENT OFFICE.

JACOB WALLACE SEEGRIST, OF PALCO, KANSAS.

BOILER-CLEANER.

1,126,302.

Specification of Letters Patent.

Patented Jan. 26, 1915.

Application filed October 21, 1914. Serial No. 867,796.

To all whom it may concern:

Be it known that I, JACOB WALLACE SEEGRIST, a citizen of the United States of America, and a resident of Palco, in the 5 county of Rooks and State of Kansas, have invented certain new and useful Improvements in Boiler-Cleaners, of which the following is a specification.

My invention relates to the cleaning of 10 boilers and the removal therefrom of the mud and other sedimentation of the water which accumulates therein, and one of the main objects is to accomplish this result without the necessity for drawing off all 15 the water and cooling the boiler as by the present method, and which method requires the services of two men for practically one half a day.

A further object is to provide a device of 20 this class which is readily operable from the exterior of the boiler at any time and whereby the boiler may be cleared of the sedimentation or deposits every day and in a very few minutes and, indeed, without the necessity 25 for drawing off more than a relatively small amount of the water contained in the boiler.

A further object is to provide such a device which may be readily installed in a 30 boiler without any material structural change therein, which does not interfere with the normal functions of the boiler, and which is comparatively inexpensive and not likely to get out of order to require repair.

35 My invention is fully described in the following specification, of which the accompanying drawings form a part, in which the separate parts are designated by the same reference characters in each of the views, 40 and in which:—

Figure 1 is a horizontal section taken through a boiler provided with my invention; Fig. 2 is a fragmentary, transverse, vertical, section taken therethrough, some- 45 what enlarged; and Fig. 3 is a fragmentary, detail, perspective, view of the device.

In the drawings forming a part of this application I have illustrated one form of embodiment of my invention, comprising a 50 transverse bar 4 having a plurality of longitudinally arranged strips 5 connected therewith by means of screws and nuts 6, Fig. 3, and preferably thereunder whereby they may rest upon the floor of the boiler 7, 55 said strips being arranged between the several rows of stay-bolts 8 which connect

the boiler with the fire-box, not shown, and I also provide supplemental strips upon the outer sides of the series of stay-bolts, as clearly shown in Fig. 1. Each of the strips 5 is provided with a plurality of upwardly directed blades 9, preferably cut from angle-iron as shown, said blades being arranged equidistant upon each strip 5 and the blades of adjacent strips being staggered, and I 60 also provide supplemental blades 10 at the point of junction of the strips and bar 4 in order to secure the effect thereof for the full length of the boiler, clear to the front thereof. Detachably secured to the bar 4, preferably by means of a small plate 11, is a forwardly directed rod 12 which passes through the front plate 13 of the boiler, a hole 14 being bored therefor and I also provide a stuffing-box 15 for said rod and I also provide 65 a nut 16 for holding the rod 12 in position when not in use.

In installing my device I first remove the hand-hole covers 17 and pass the strips 5 therethrough, said strips being made of flexible material in order to be enabled to pass the same around the forward stay-bolts to arrange said strips between the rows thereof, after which the bar 4 is passed into the 70 boiler and the strips secured thereto by means of the bolts and nuts already referred to, the rod 12 passed through the hole 14 and secured to the said bar, the hand-hole covers replaced, and the device is ready for use.

When it is desired to clear the boiler, usually when not in use, the nut 16 may be loosened and the entire device reciprocated forwardly and backwardly within the boiler by the handled rod 12 to churn the water 75 in the boiler, thus washing up the sedimentation and holding the same in suspension in the water; after the water has been sufficiently churned, the outlet valve or valves 18 are opened and the discolored 80 water bearing the sedimentation is drawn off, and I have found by experience that but 85 comparatively few gallons of water are required to be drawn off for each clearing of the boiler, and it will be noted that this operation takes but a moment and does not necessitate the removal of the hand-hole covers, thus resulting in a material saving for the packing thereof which needs to be frequently replaced when the said covers are 90 removed for the boiler clearing by the conventional method.

My invention is very simple and is readily adapted to boilers of different types and shapes, the only alteration over the form shown being in the number of the bladed strips and in the length and shape of the transverse bar to which they are connected whereby said strips will rest and be slideable upon the floor of the boiler and at the bottom of the sides thereof in order to agitate the water throughout the entire length and width of the boiler.

While I have shown a present preferred form of construction, it will be obvious that I am not limited thereto, but may make changes thereover, within the scope of the following claims, without departing from the spirit of my invention, or sacrificing its advantages.

Having fully described my invention, what I claim as new, and desire to secure by Letters Patent, is:—

1. The combination in a boiler, of a transverse bar, a plurality of strips arranged perpendicular thereto and in detachable connection therewith, blades on said strips for agitating the water in the boiler, and means, external of said boiler, for reciprocating said bar and strips.

2. The combination in a boiler, of a transverse bar, a plurality of strips arranged

perpendicular thereto and in detachable connection therewith, and resting upon the floor of said boiler, upwardly directed blades on said strips, and means, external of said boiler, for reciprocating said bar and strips to agitate the water in said boiler.

3. The combination in a boiler, of a transverse bar, a plurality of strips arranged perpendicular thereto and in detachable connection therewith, upwardly directed blades on said strips and arranged in staggered relationship on adjacent strips, and means, external of said boiler, for reciprocating said bar and strips to agitate the water in said boiler.

4. As an article of manufacture, for use in a boiler, a bar of flexible material, a plurality of flexible strips in detachable connection therewith at desired intervals and in perpendicular arrangement thereto, and a handled rod in detachable connection with said bar, each of said strips having a plurality of blades thereon and at an angle thereto.

In testimony whereof I have signed my name to this specification in the presence of two subscribing witnesses.

JACOB WALLACE SEEGRIST.
